MEANS FOR FINISHING HOT ROLLED BARS

Oscar U. Cook, Birmingham, Ala.

Application November 1, 1937, Serial No. 172,294

1 Claim. (CL 29—33)

This invention relates to means for finishing hot rolled bars. It aims to provide an improved combination of cooperating parts for producing bars of accurate cross-sectional contour. The various features of the invention will be fully apparent from the following detailed disclosure when read in connection with the accompanying drawing, in which—

Fig. 1 is a view in side elevation of apparatus well suited for carrying out the novel method; Figs. 2 and 3 are detail views of dies successively arranged and parted on planes at an angle with one another; Figs. 4 and 5 are enlarged cross-sectional views of the bar in different stages of manufacture; Fig. 6 is a section on line 6—6 of Fig. 1.

In the conventional method of hot rolling bars, it is difficult to bring the work to the required diameter and it is necessary to allow considerable tolerance. By the use of the method and apparatus of the present invention hereinafter more fully set forth, the necessary tolerance will be very materially reduced and the finish of the bar will be much smoother and the surface oxide very tight.

In rolling bars according to my improved method, the stock S is hot rolled between a pair of coacting planishing rolls 10 and 11. Before entering these planishing rolls, the bar is subjected to a scale breaking and scraping operation by engagement with the fixed parts 7 and 8 and the movable part 9, which jointly constitute a scale breaker. As the stock enters the planishing rolls 10 and 11, the movable part of the scale breaker is brought substantially to the position shown in the drawing, in which it is effective to bend the entering stock and to break and scrape the scale therefrom. As the bar stock emerges from the planishing rolls, it enters suitable cooling or controlled atmosphere apparatus, indicated at 12, and during the movement of the work through this cooling or controlled atmosphere apparatus the temperature of the bar is so reduced and its condition is so changed as to minimize the forming of oxide and prevent any undue stretching of the stock by subsequent operations. After the bar stock leaves the cooling apparatus 12, it successively engages dies 13 and 14. These dies are parted on lines or planes 15 and 16, which are disposed in staggered relation to one another, these planes preferably being approximately at right angles. The dies 13 and 14 are provided with approximately circular openings 17 and 18.

For practical reasons, where the openings intersect the parting planes, it is generally neces-

sary to provide slight enlargements, indicated at 19 and 20.

In practice, in order to start the bar stock through the dies, it is necessary that they be opened or slightly separated. Suitable means are provided for automatically closing the dies. The enlargements 19 and 20 of the die openings have a tendency to produce fins 19a and 20a on the bar stock. However, the relative disposition of the dies is such that the fins 19a are smoothed out or partly obliterated by the successive die 14. After the bar stock leaves the die 14, it is engaged by a pair of cooperating finishing rolls 21 and 22, which have a circular active pass, as indicated in Fig. 6. These finishing rolls draw the bar stock through the dies and through the cooling means, they smooth out and obliterate the longitudinal fin 20a formed by the die 14 and they impart the final finish and desired cross-sectional contour to the bars. While the method and apparatus disclosed is peculiarly well suited for rolling so-called "rounds" or bars of truly circular cross-section, it will be understood that hot rolled products of other cross-sectional forms can be produced by providing suitable shaped openings in the dies and by varying the contour of the active passes of the planishing rolls 10 and 11, and of the finishing rolls 21 and 22.

While I have described quite specifically certain steps in the method and particular apparatus used for the practice of the invention, it is to be understood that various modifications and substitutions of equivalents may be made by those skilled in the art without departure from the invention as defined in the appended claim.

What I claim is:

An apparatus for producing bars of predetermined finished cross-sectional shape comprising in combination a pair of coacting rolls through which the bars are adapted to be passed, cooling means positioned to receive the bar as it emerges from said rolls, a plurality of dies arranged in succession and positioned to engage the work as it emerges from the cooling means, each of said dies having an opening therein conforming approximately to the cross-sectional contour of the finished product to be produced, said dies being parted along planes disposed in staggered relation to one another so that the longitudinal fin produced by one die is smoothed down by a succeeding die and a pair of finishing rolls adapted to receive the work as it emerges from said dies, said rolls having an active pass conforming to the desired contour of the bar being rolled.

OSCAR U. COOK.
